(57) **ABSTRACT**

A sighting/training device configured to be mounted to a pistol handle of a gun incorporates a light source, a power source, and a control. The device has at least two operating modes and a switch to select one of the modes. In a first operating mode the light source emits light when a button grip is pressed by a user, and does not emit light when the button grip is not depressed. In a second mode the light source emits light when a sound, such as the sound of a gun firing pin, is detected.

5 holes use 20K					
2 Do not populate S2					
Theory of Operation: the master module.					
With a single push of S4 it will turn on the trainer mode with 2 laser pulses. After 5 mins. in unused trainer mode it returns to sight mode.					
With another push of button it returns to sight mode, with a 1 laser pulse.					

FIG. 7

LIGHT SIGHTING AND TRAINING DEVICE

CROSS REFERENCE TO RELATED APPLICATIONS

Each of the following applications are incorporated herein by reference: U.S. application Ser. No. 14/963,475 filed on Dec. 9, 2015, now U.S. Patent Application Publication No. 2016-0161220 entitled "Master Module Light Source and Trainer"; U.S. application Ser. No. 14/459,274 filed on Aug. 13, 2014, now U.S. Pat. No. 9,297,614 entitled "Master Module Light Source, Retainer and Kits"; U.S. application Ser. No. 15/804,229 filed on Nov. 6, 2017 and entitled "Boresighter Trainer for Gun."

BACKGROUND OF THE INVENTION

There are laser sights used with a gun when firing bullets, and laser trainers, used with a gun when, instead of firing a bullet when the firing pin is activated, a laser light beam is generated. Light (particularly laser) sighters and laser trainers for guns have in the past been different products, requiring the owner of a firearm to purchase at least two separate products.

SUMMARY OF THE INVENTION

The present invention is a single device configured to be part of a grip for a pistol handle. The pistol handle may be utilized with any type of suitable weapon, such as a real gun or toy gun (including BB guns and paint-ball guns). The grip may be used with any suitable style of gun, such as an automatic pistol, revolver, machine pistol, or assault-style rifle that incorporates a light source (preferably a laser), a power source (such as one or more batteries), and a control unit (which has one or more switches) that controls the operation of the light source.

The sighter/trainer has at least two modes that are selected by a user operating a first switch to select between the modes. In a first mode, the light source is on constantly when a user activates a second switch, so a user can sight a target with a light (preferably laser light) emitted by the sighter/trainer. In a second mode, the sighter/trainer emits laser light for a short duration when it is activated by a sound, such as the sound of the firearm firing pin striking. The sighter/trainer may also have a third mode in which it is turned off. The sighter/trainer is not limited to any particular structure, although the preferred structure is as described herein.

Utilizing the sighter/trainer, the owner of a firearm need purchase only one product to: (1) sight a target; and (2) train using light instead of live ammunition. Dealers could reduce their inventory of products because only a single product is required for firearm sighting and firearm training. Moreover, the sighter/trainer is configured so a single product attached to the pistol grip of a gun is suitable for use both by right-handed and left-handed people, which further reduces the number of products and inventory.

A sighter/trainer according to the invention could be (1) sold separately as an individual product, (2) sold assembled on a gun, (3) sold as a kit with multiple sighter/trainer units, each of which could fit a different style or size of pistol handle, or (4) sold as a kit with the sighter/trainer and a gun with a pistol handle on which the sighter/trainer fits.

BRIEF DESCRIPTION OF THE DRAWINGS

FIG. 1 is an exploded view of a sighter/trainer in accordance with aspects of the invention.

FIG. 1A is side view of a panel of FIG. 1.

FIG. 1B is a side view of the circuit board of the sighter/trainer of FIG. 1.

FIG. 2 is a perspective, side view of the sighter/trainer of FIG. 1.

FIG. 3 illustrates exemplary circuitry for the circuit board of FIGS. 1B and 2.

FIG. 4 illustrates exemplary circuitry for the circuit of FIGS. 1B and 2.

FIG. 5 illustrates exemplary circuitry for the circuit of FIGS. 1B and 2.

FIG. 6 is a close-up, partial side, perspective view of a laser module and printed circuit board according to the aspects of the disclosure.

FIG. 7 is a list of exemplary components referenced in FIG. 6.

DETAILED DESCRIPTION OF PREFERRED EMBODIMENTS

Turning now to the drawings where the purpose is to describe preferred embodiments of the invention and not to limit same, FIG. 1 is an exploded view of a sighter/trainer 10 according to aspects of the invention. Sighter/trainer 10 has a panel 20, a circuit board 50, and a laser module 100. Sighter/trainer 10 is configured to fit on a pistol handle of a gun as one-half of the grip on the handle. Sighter/trainer 10 may be for any suitable real gun or toy gun, such as a semi-automatic pistol that uses a magazine of bullets, a revolver, a machine pistol, or a rifle (such as an assault-style rifle), which includes a pistol handle. The sighter/trainer 10 may be configured to fit pistol handles of essentially any shape or size.

Panel 20 as shown is configured to be on the right-hand side of the pistol handle (viewed in the direction of fire of the pistol), and it thus forms one side of the grip for the pistol handle. Alternatively, the panel 20 and sighter/trainer 10 could be configured for panel 20 to be on the left-hand side of the pistol handle. This configuration is not shown in the drawings but would be understood by one skilled in the art based on this disclosure.

Panel 20 has an outer surface 22, at least part of which is preferably textured to provide a better grip by a human hand. Panel 20 also has an inner surface 24 that forms a cavity 49 to house various components, as explained below. Panel 20 further includes a top portion 26 with opening 28A formed in top surface 26A, opening 28B formed in side surface 26B, opening 28C in front surface 26C, front edge 30, rear edge 32, bottom 34, and opening 36 through which a battery can be inserted or removed.

Openings 38 and 44 are for receiving fasteners and securing panel 20 to the pistol handle. There is also an indentation 46 for a better fit for this embodiment on the pistol handle and/or to accommodate other fasteners or components of the pistol handle. Opening 40 and button 150 are positioned such that a right-handed shooter can press button 150 with the palm side of the fingers when holding the gun handle, and a left-handed shooter can press button 150 with the fingers of the left hand (which wrap around front edge 30) when holding the pistol handle. A grip configured to be on the left-hand side of a pistol handle would function in a mirror-image manner.

At least one circuit board 50 is configured to be received in cavity 49 formed by side 24 of panel 20. In the embodiment shown, there is a single circuit board 50, but a circuit board according to this disclosure could include multiple sections (i.e., multiple circuit boards) that are electrically

connected. For example, there could be two or three separate circuit boards that provide the functionality of the at least one circuit board **50**. Circuit board **50** has a first side **52**, a second side **53**, a top edge **54**, a bottom edge **56**, a front edge **58**, a back edge **60**, three compression switches **62** disposed on first side **52**, opening **64**, bracket **66**, compression switch **68**, and openings **70** to receive fasteners **160**, which pass through openings **70** and are received in screw bosses **51** on second side **24** of panel **20** in order to secure circuit board **50** to panel **20**. A negative power connector **220** with opening **222** is in circuit board **50** and receives a fastener **160** through opening **222** which fastens to a screw boss **51**. Fastener **160** preferably touches or is connected to circuit board **50** and transfers current to circuit board **50**.

Button **150** and switches **62** are positioned for ease of use both by right-handed and left-handed persons. Button **150** is preferably between $\frac{3}{4}$ " and $1\frac{1}{4}$ " in length (at its greatest length, which is measured across dimples **150A**) and could have a length at its greatest length of $\frac{1}{2}$ ", $\frac{5}{8}$ ", $\frac{3}{4}$ ", $\frac{7}{8}$ ", 1", $1\frac{1}{8}$ ", $1\frac{1}{4}$ ", $1\frac{1}{2}$ ", $1\frac{1}{3}$ ", $1\frac{3}{4}$ ", $1\frac{7}{8}$ ", 2", or any length between $\frac{1}{2}$ " and 2". The width of switch **62** at its widest point (as measured across any of dimples **150A**) is about $\frac{1}{2}$ " to $\frac{5}{8}$ ", but could have a width of $\frac{3}{8}$ ", $\frac{1}{2}$ ", $\frac{5}{8}$ ", $\frac{3}{4}$ ", $\frac{7}{8}$ ", 1", $1\frac{1}{8}$ ", or any width between $\frac{3}{8}$ " and $1\frac{1}{8}$ ". The distance from top **26A** to top edge **150B** of button **150** is about 25%-35% of the distance from top **26A** to bottom **34** measured in a straight line, but could be about 20%, 25%, 30%, 35%, 40% or any percentage between 20% and 40%. The distance from side **30** the center of button **150** as measured in a straight line is about 20%-30% of the distance from side **30** to side **32** as measured in a straight line through the center of button **150**, but the distance could be 15%, 20%, 25%, 30%, 35%, 40%, or any percentage between 15% and 40%. Button **150** preferably has one or more dimples **150A** on its inside surface, wherein each dimple is configured to align with a switch **62** when sighter/trainer **10** is assembled. When the outer side of button **150** is pressed by a user, one or more of dimples **150A** depresses one or more switches **62** to activate light source **100** when sighter/trainer **10** is in a first operational mode.

Electrical circuitry **55** (examples of which are shown in FIGS. 3-5) is contained in, disposed on, and/or coupled to circuit board **50**, for example on first side **52** of circuit board **50** and optionally in part on second side **53**. For example, circuit board **50** may be coupled to and/or electrically interconnect various resistors, capacitors, diodes, inductors, microprocessors, microcontrollers, transistors, integrated circuits, and/or the like in order to implement desired functionality for sighter/trainer **10**. FIGS. 40 and 41 of U.S. Application Publication 2016-0161220 entitled "Master Module Light Source and Trainer" also show an exemplary circuit diagram and corresponding part listing for an exemplary sighter/trainer **10**.

Switch **68** rests against and can be depressed by button **170**, which can be accessed through opening **42** when sighter/trainer **10** is assembled, to change the operational mode of sighter/trainer **10**, for example to be either in a first operational mode as a laser sighter or in a second operational mode as a laser trainer. Switches **62** on side **52** of circuit board **50** are positioned against and can be depressed by button grip **150** to contact the circuitry on side **52** and transfer power from battery **180** when sighter/trainer **10** is in its first operational mode, as discussed below.

Battery **180** is preferably a coin cell battery, for example a CR2032 battery, and is received as shown in FIG. 1A. Battery **180** could be any suitable type of battery and is most preferably a lithium 6V coin cell battery, but could have a

voltage between 3V and 6V. Battery **180** has a first (positive) terminal on side **182**, second (negative) terminal on side **184**, and can be inserted and removed from sighter/trainer **10** by removing panel **20** and then removing and/or inserting another battery **180**. Light module **100**, which as shown is a laser module that projects red laser light (although any suitable laser may be used), fits against laser ball seat tab **102**, and has a first end **108** with an opening **108A** through which light is emitted, and a spring **104** extending from its second end **104A**. Spring **104** is received in opening **67**, which is conductive and preferably plated, to provide a conductive path through the circuitry to light module **100**.

Positive battery contact **190** has a flange **192**, a first side **194**, and an aperture **196**. Fastener **198** passes through opening **196**, through insulating thread insert **200**, and is received in a boss in cavity **49** of panel **20**. Negative battery contact **210** is electrically conductive, has a stem **212** and a partial loop **214**. When sighter/trainer **10** is assembled, a fastener **160** passes through opening **222** and through partial loop **214**, and is secured in a boss **51** on panel **20**. In this manner, when sighter/trainer **10** is assembled, the second (negative) side **184** of battery **180** touches stem **212** of positive battery contact **210** and partial loop **214** is positioned against positive energy transfer structure **220** to provide a conductive path through screw **160** and facilitate flow of electrical current to circuit board **50**.

Similarly, when sighter/trainer **10** is assembled, surface **194** of positive battery contact **190** is positioned against first (positive) side **182** of battery **180** and back surface **199** is positioned against circuit board **50** to provide a conductive path and complete the circuit, thus providing electrical power to circuit board **50** and components electrically connected thereto.

When sighter/trainer **10** is assembled, light module **100** is retained in pocket **27** of upper section **26** of panel **20**. A set screw **106** is positioned in opening **28A** and can be tightened or loosened to move the first end **108** of light module **100** up and down. Another set screw **106** is positioned in opening **28B** and can be tightened or loosened to move first end **108** of light module **100** side to side.

In accordance with aspects of the invention, sighter/trainer **10** is configured to have multiple operational modes. Button **170** can be depressed through opening **44** so that it compresses switch **68**, which causes sighter/trainer **10** to be in the first operational mode. When in the first operational mode, laser module **100** is continuously activated when a user presses button grip **150** sufficiently to depress one or more of switches **62**, which causes electrical current to flow from battery **180** to light source **100** and cause light source **100** to emit a beam of light. In this manner, sighter/trainer **10** may emit a continuous laser beam for targeting (or sighting) purposes. In this mode, when a switch **62** is not depressed, no electrical current (and/or only minimal electrical current) flows to light source **100** and light source **100** is off.

Button **170** can also be pressed to depress switch **68** and cause sighter/trainer **10** to be in a second operational mode. In the second operational mode, light module **100** is activated for a limited-duration pulse responsive to detection of a particular acoustic signature received at microphone **702** (for example, as seen in FIGS. 36 and 39 of U.S. Patent Application Publication No. 2016-0161220). In this manner, sighter/trainer **10** may be utilized to emit a pulse from laser module **100** only after detection of a sound, such as the sound of operation of a firing pin.

Button **170** of sighter/trainer **10** may be pressed to depress switch **68** to change the operational mode of sighter/trainer

10 back and forth from the first operational mode to the second operational mode, depending on what the user desires. Sighter/trainer **10** may also have a third operational mode in which sighter/trainer **10** is off and electrical current does not flow to light source **100** even if one or more switches **62** are depressed. In that case, the user can press switch **170** to go from, for example, the first operational mode, then to the second operational mode, to the third operational mode, and then back to the first operational mode.

Sighter/trainer **10** may utilize a microprocessor **700** configured to control operation of sighter/trainer **10**, for example a PIC12F1571 microprocessor offered by Micro-Chip Corporation (Chandler, Ariz.). However, any suitable microprocessor **700** may be used. Microprocessor **700** is responsible for governing operation of sighter/trainer **10**, including activation and deactivation of light source **100**, changing sighter/trainer **10** from a first operational mode to a second operational mode responsive to switch or button inputs, and so forth. Microprocessor **700** may accommodate the control inputs from microphone **702** as well as switch (es) **68**, as well as other control inputs and signal outputs utilized in sighter/trainer **10**. Microprocessor **700**, microphone **702**, light source **100**, and other components of sighter/trainer **10** may be mechanically and electrically coupled to one another via circuit board **50** and the traces thereon and/or therein, for example as illustrated in FIGS. 3-5 herein (and/or in FIGS. 37, 38, 40, 41, 43, and 44 of U.S. Patent Application Publication No. 2016-0161220). Additionally, various connective wires may be utilized, as needed, in order to provide desired electrical connections within sighter/trainer **10**.

Thus, in accordance with these aspects a single sighter/trainer **10** may be used as a targeting laser using live ammunition, yet also suitable for training without live ammunition. Additionally, sighter/trainer **10** is configured for ambidextrous operation, being suitable for use by both right-handed and left-handed shooters without modification.

Some specific, nonlimiting examples of the invention follow:

1. A sighter/trainer device configured to be attached to the pistol handle of a gun, wherein the grip comprises:
  - (a) a panel;
  - (b) at least one circuit board configured with circuitry having a first operational mode and a second operational mode;
  - (c) a laser in communication with the circuit board;
  - (d) a power source in communication with the circuit board; and
  - (e) a switch in communication with the circuit board, the switch being moveable to change the operational mode of the circuitry.
2. The sighter/trainer device of example 1 that includes a second button that can be depressed to cause electrical current to be delivered to the laser when the at least one circuit board is in its second operational mode.
3. The sighter/trainer device of example 2, wherein the second button has a length of 1" or more and a width of 1/2" or more.
4. The sighter/trainer device of example 2, wherein the second button has a height of 1 1/4" to 3".
5. The sighter/trainer device of example 2, wherein the second button presses against a plurality of switches on the circuit board.
6. The sighter/trainer device of example 2, wherein the second button presses against three switches on the circuit board.

7. The sighter/trainer device of example 2, wherein the panel has a front edge and the second button is positioned no more than 3/4" behind the front edge.
8. The sighter/trainer device of example 2, wherein the panel has a bottom and the second button is positioned at least 2" from the bottom.
9. The sighter/trainer device of example 2, wherein the panel has a height and the second button is positioned entirely in the top half of the height.
10. The sighter/trainer device of example 2, wherein the panel has a width and the second button is positioned entirely in the front half of the width.
11. The sighter/trainer device of example 6, wherein the through bolt hole is plated.
12. The sighter/trainer device of example 7 or 8, wherein a spring is retained in the through bolt hole.
13. The sighter/trainer device of example 8, wherein the spring is soldered in the through bolt hole.
14. The sighter/trainer device of example 8 or 9, wherein the spring biases the light source away from the spring.
15. The sighter/trainer device of any of examples 8-10, wherein the spring provides a negative electrical contact for the light source.
16. The sighter/trainer device of example 1, wherein electrical current from the power source travels through the first circuit board to reach the light source.
17. The sighter/trainer device of example 15, wherein electrical current from the power source travels through the first circuit board and second circuit board to reach the light source.
18. The sighter/trainer device of any of examples 1-16, wherein the light source is a laser.
19. The sighter/trainer device of any of examples 1-18, wherein the power source is in a grip that is connected to the first circuit board.
20. The sighter/trainer device of any of examples 1-19, wherein the power source is one or more batteries.
21. The sighter/trainer device of example 20, wherein each adjustment device is a set screw.
22. The sighter/trainer device of example 20 or 21, wherein one of the adjustment devices moves the light source from side to side and the other adjustment device moves the light source up and down.
23. The sighter/trainer device of any of examples 1-22 that is configured to cause the light source to operate in any of the following modes: stay constantly on, stay constantly off, or turn from the on position to the off position after a predetermined period of time.
24. The sighter/trainer device of any of examples 1-24 that includes one or more switches to change the mode of operation of the light source.
25. The sighter/trainer device of example 25, wherein the one or more switches is on the first circuit board.
26. The sighter/trainer device of any of examples 1-25, wherein the power source is one battery.
27. The sighter/trainer device of any of examples 1-26, wherein the power source is enclosed in a panel cavity.
28. The sighter/trainer device of any of examples 1-27, wherein the power source is surrounded by an insulating sleeve.
29. The sighter/trainer device of any of examples 1-28, wherein the grip includes a cap on its end for removing and replacing the power source.
30. The sighter/trainer device of any of examples 1-29, wherein the light source has a first end through which light is emitted and the first end is retained partially in a module cushion ball.

Having thus described preferred embodiments of the invention, other variations and embodiments that do not depart from the spirit of the invention will become apparent to those skilled in the art. The scope of the present invention is thus not limited to any particular embodiment, but is instead set forth in the appended claims and the legal equivalents thereof. Unless expressly stated in the written description or claims, the steps of any method recited in the claims may be performed in any order capable of yielding the desired result.

What is claimed is:

1. A sighting/training device configured to attach to a pistol handle of a gun, the device including:
    - (a) a panel configured to be one side of a grip on the pistol handle;
    - (b) a power source;
    - (c) a light source; and
    - (d) a control to transfer electrical current from the power source to the light source, the control having (i) a first operational mode and a second operational mode, (ii) a first switch to select either the first operational mode or the second operational mode, wherein when the light source is in (iii) the first operational mode it emits light when a second switch is activated to direct electrical current from the power source to the light source, and does not emit light when the second switch is not activated, and (iv) the second operational mode it emits light when it detects the sound of a gun firing pin.
  2. The sighting/training device of claim 1, wherein the control is at least one circuit board in electrical communication with the light source, the first switch, the second switch, and the power source.
  3. The sighting/training device of claim 2, wherein the light source has a first end through which light is emitted and a second end, and the at least one circuit board has a through bolt hole in communication with the second end.
  4. The sighting/training device of claim 3, wherein the through bolt hole is plated.
  5. The sighting/training device of claim 3, wherein a spring is in contact with the second end of the light source and is retained in the through bolt hole.
  6. The sighting/training device of claim 5, wherein the spring biases the light source away from the through bolt hole.
  7. The sighting/training device of claim 5, wherein the spring provides a negative contact for the light source.
  8. The sighting/training device of claim 1, wherein the light source is a laser.
  9. The sighting/training device of claim 1, wherein the power source and light source are each inside of a cavity of the panel.
- 5
10. The sighting/training device of claim 1, wherein the power source is at least one battery.
  11. The sighting/training device of claim 2, wherein the circuit board includes a capacitor.
  12. The sighting/training device of claim 1 that includes a first button that can be pressed to cause the first switch to cause the control to change between the first operational mode and the second operational mode, and a second button that can be depressed to operate one or more second switches that cause electrical current to flow through the at least one circuit board to the light source when the circuit board is in its second operational mode.
  13. The sighting/training device of claim 12, wherein the second button has a length of 1" or more and a width of $\frac{1}{2}$ " or more.
  14. The sighting/training device of claim 12, wherein the second button has a height of $1\frac{1}{4}$ " to 3".
  15. The sighting/training device of claim 12, wherein the second button is positioned against a plurality of switches on the circuit board.
  16. The sighting/training device of claim 12, wherein the second button is positioned against three switches on the circuit board.
  17. The sighting/training device of claim 12, wherein the panel has a front edge and the second button is positioned no more than $\frac{3}{4}$ " behind the front edge.
  18. The sighting/training device of claim 12, wherein the panel has a bottom and the second button is positioned at least 2" from the bottom.
  19. The sighting/training device of claim 12, wherein the panel has a height with a top half and the second button is positioned entirely in the top half of the height.
  20. The sighting/training device of claim 12, wherein the panel has a width with a front half and the second button is positioned entirely in the front half of the width.
  21. The sighting/training device of claim 1, wherein the laser is activated for between about 7.5 milliseconds to about 12.5 milliseconds, or for about 0.1 seconds, when the circuit is activated in the second operational mode.
  22. The sighting/training device of claim 2, wherein the at least one circuit board has circuitry that is a 3V-6V system.
  23. A gun having a pistol handle with the sighting/training device of claim 1 attached to it.
  24. The gun of claim 23 that is selected from one or more of the group consisting of: an automatic pistol, a revolver, a machine pistol, an assault-style rifle, a BB gun, an airsoft rifle, and a paint-ball gun.
  25. A kit including the sighting/training device of claim 1 and a gun with a pistol handle configured to have the sighting/training device attached to it.
